UNITED STATES PATENT OFFICE.

WILLIAM H. MANN AND ULYSSES G. MUCK, OF DORRANCE, KANSAS.

GRAIN-DOOR FOR CARS.

SPECIFICATION forming part of Letters Patent No. 699,336, dated May 6, 1902.

Application filed December 17, 1901. Serial No. 86,266. (No model.)

To all whom it may concern:

Be it known that we, WILLIAM H. MANN and ULYSSES G. MUCK, citizens of the United States, residing at Dorrance, in the county of 5 Russell and State of Kansas, have invented certain new and useful Improvements in Grain-Doors for Cars, of which the following is a specification.

Our invention relates to grain-doors for 10 cars; and our objects are to produce a structure of this character which will prevent leakage of the grain, which can be easily and quickly opened or closed, and which is of simple, strong, durable, and cheap construc- 15 tion.

With these objects in view the invention consists in certain novel and peculiar features of construction and combinations of parts, as hereinafter described and claimed, and in order 20 that the invention may be fully understood reference is to be had to the accompanying drawings, in which—

Figure 1 is a vertical longitudinal section of a car equipped with a grain-door embodying our invention. Fig. 2 is a horizontal section of the same on line II II, of Fig. 1. Fig. 3 is an enlarged horizontal section to show the locking-rod and the perforated bracket to which it is locked. Fig. 4 is an exterior side 30 view of a car to show the corresponding side of the door.

In the said drawings, 1 designates the car of the usual or any preferred construction and provided with the customary door-opening 2 in its side. At one side of the door-opening an inclined track 3 is provided against the side wall, said track being provided with a guard flange or rail 4 and having its low end contiguous to the door-opening 40 and its high or opposite end closed by the inwardly-projecting portion 4^a of said rail 4. At the opposite side of the door-opening is a vertical retaining-strip 5 of acute-angular form in cross-section, so as to provide a V-shaped groove, and bent at its upper end to form a flange 6, closing the upper end of said groove. The door 7, normally bridging said door-opening, is tapered at its front end, as at 8, so as to fit snugly in said V-shaped 45 groove, the flange of the retaining-strip overlapping and therefore tending to hold that end of the door depressed. At its opposite

end the door is provided with a stub-shaft 9, which projects outwardly over track 3 and its flange 4 and carries a roller 10 to run upon 55 said track and be held reliably in engagement therewith by said guard flange or rail.

To clamp the door tightly in position and therefore guard against leakage of grain, a vertical rod 11, provided with one or more 60 cams or eccentrics 12, is journaled at the lower end in a plate 13, set in the floor of the car and at its upper end in a bracket 14, secured to the car above the door. The upper end of said rod is provided with a crank arm 65 or handle 15, by which it is turned, and said crank arm or handle is provided with a perforation 16, adapted to register with perforations 17 in said bracket in order that a pin 18 may simultaneously engage the perforation 70 of the crank arm or handle and one of the perforations 17 of the bracket, so as to lock the rod with the eccentrics or cams disposed so as to clamp the door outwardly against the car or leave it free to be moved. The pin 18 75 is attached by a chain 19 to the car-frame in order to avoid being misplaced or lost. It being obvious that the frictional action of the eccentrics or cams would otherwise soon render them functionless, because of the cavities worn in the door; the latter at the proper points are provided with metallic wear-plates 80 20, as shown clearly in Figs. 1 and 2.

In practice it is apparent that when the door is clamped in position, as shown in Fig. 85 2, there is no possibility of it working upward against gravitation, the weight of the grain, the overlapping flange 6 of the retaining-strip, and the eccentrics or cams 12 engaging the recessed wear-plates 20; nor is there any 90 chance of the door being released, because the pin 18 by engagement with the perforations of crank-arm 15 and bracket 14 prevents any accidental movement of the clamping-rod.

To discharge the grain after the outside 95 doors (not shown) are opened, the person in charge reaches through opening 2 and removes pin 18. He then pulls crank arm or handle outwardly or toward the door-opening, so as to swing the cams or eccentrics from 100 the position shown in full to the position shown in dotted lines, Fig. 2, and thus relieves the door of the clamping pressure applied by said cams or eccentrics. He then

sticks a crowbar (not shown) into cavity 21, formed in the outer lower corner of the door contiguous to the clamping mechanism, and to relieve the door of undue wear a metallic plate 22 reinforces it at such point. By the proper manipulation of this crowbar he tilts the door to the position shown in dotted lines, Figs. 1 and 4, the overlapping flange 6 preventing the forward end of the door from rising. A large quantity of grain of course begins to fall as soon as the door is pried up in this manner, and thus relieves the door of sufficient pressure at its inner side to enable the attendant to shove the door rearwardly, the roller 9 obviously traveling upon the track and eliminating friction in a large degree, the forward end of the door dragging lightly upon the floor. When the door is fully opened, it may be so secured by causing the engagement of its forward wear-plates 20 with the eccentrics or cams 12 by the proper manipulation of the rod, as hereinbefore explained. To close the door, the cams or eccentrics are disengaged from the wear-plates 25 and the door slid forwardly upon the track until it is arrested by the engagement of its front end by the retaining-strip, the beveled front end of the door facilitating its reengagement, as will be readily understood.

30 From the above description it will be apparent that we have produced a grain-door for cars which embodies the features of advantage enumerated as desirable in the statement of invention, and while the preferred embodiment of the same is shown and described it is to be understood that it is susceptible of change in minor particulars without departing from the principle of construction involved.

35 40 Having thus described the invention, what

we claim as new, and desire to secure by Letters Patent, is—

1. In a grain-door for cars, the combination with a door-opening, a retaining-strip at one side of the opening, an inclined track at the other side, and a roller mounted on said door and engaging said track; of a vertical rod having its lower end journaled in a plate sunk in the floor of said car and provided with cams or eccentrics, a bracket holding the upper end of said rod and provided with perforations, a perforated crank-arm secured to the upper end of said rod, a pin for simultaneously engaging the perforation of said crank-arm and one of the perforations of said bracket, and wear-plates on the door opposite said cams, all as and for the purpose set forth.

2. In a grain-door for cars, the combination with a door-opening, a retaining-strip at one side of the opening, an inclined track at the other side, a guard-rail along its length, a door bridging said opening and engaging said retaining-strip, a stub-shaft mounted on the upper corner of said door, and a roller mounted on said stub-shaft and engaging said track; of a vertical rod having its lower end journaled in a plate sunk in the floor of said car and provided with cams or eccentrics, a bracket holding the upper end of said rod, a crank-arm secured to the upper end of said rod, and wear-plates on the door opposite said cams, all as and for the purpose set forth.

In testimony whereof we affix our signatures in the presence of two witnesses.

WILLIAM H. MANN.
ULYSSES G. MUCK.
